UNITED STATES PATENT OFFICE.

PHILIP W. DALRYMPLE, OF BALTIMORE, MARYLAND.

SOOT BLOWER.

Application filed September 12, 1919. Serial No. 323,290.

To all whom it may concern:

Be it known that I, PHILIP W. DALRYMPLE, a citizen of the United States of America, residing in the city of Baltimore, State of Maryland, have invented certain new and useful Improvements in Soot Blowers, of which the following is a specification.

In the generation of steam for power plants, one of the difficulties encountered is due to the accumulation of soot, as carbon, ashes and other solid products of combustion on the heating surfaces. This accumulation acts as a most effective insulation and reduces the efficiency of the plant in proportion to the extent of the accumulation. It has been customary in the past to clean the heating surfaces from time to time by brushing or scraping, and cooling the boiler to permit access for this purpose. Such cooling means the loss of several hours operation of the generating unit, and in the majority of plants must be avoided if possible.

For use in preventing such accumulations or in removing them from time to time before they become so extensive as to make shutting down of the unit and cooling the boiler necessary, apparatus known as soot blowers has been provided in various forms. Such soot blowers commonly consist of a battery of nozzles connected to a steam header and directed at the heating surfaces on which the accumulation referred to is most extensively deposited. When it is desired to remove the accumulation, steam is projected from the nozzles against the surfaces to be cleaned, unseating the particles so that they drop into the fire or are carried up the flue.

Steam boilers are divided into two well known types, fire tube and water tube. The heating surfaces of fire tube boilers are comparatively convenient of access for the purpose of blowing out such accumulations, but water tube boilers are less accessible for this operation. One of the difficulties is that the blowing nozzles, to be effective, must be located in the hot part of the furnace. Owing to the contour of the heating surface to be cleaned and its distribution, the direction of the steam blast from the various nozzles must be changed, that is, the surface must be swept by the blast which is directed from time to time against the different portions of the surface to be treated. Various devices embodying nozzles, each adapted to be swung through an arc or having a uni-

versal connection, have been installed, but the intense heat to which they are subjected has had the effect of making the moving parts inoperative, and cleaning of the heating surfaces by the old or direct method of cooling the furnace and scraping them has been necessary even with such installations.

The present invention provides a nozzle, or more correctly, an arrangement of nozzles by which a steam blast or a blast of any fluid under pressure may be controlled as to its direction without changing the position or relation of the nozzles, etc., and without any moving parts in the vicinity of the nozzles or their supports. Such an arrangement of nozzles has been shown in the accompanying drawings in connection with a water tube boiler, the same comprising, with the necessary connections, valves, etc., an improved soot blowing apparatus.

In accordance with the invention the nozzles are arranged in groups so that the jets or blasts from each of a plurality of nozzles combine preferably near the mouths or points of the nozzles, and the direction of the resultant blast is controlled by changing the relative pressure at which the fluid composing the blast is supplied to and released from the respective nozzles forming such a group, a change of direction being accomplished by giving preponderance as to speed and momentum to one or more of the combined streams or blasts over that from the remaining nozzle or nozzles in the particular group of converging nozzles.

In the accompanying drawing I have illustrated a water tube boiler to which a soot blowing apparatus embodying my invention is applied.

Figure 1 is a side elevation, partly in section, of a furnace and water tube boiler equipped with a soot blower in accordance with my invention.

Figure 2 is a transverse section on the line 2, 2 of Figure 1.

Figure 3 is a diagrammatic view of one group of nozzles with the distributing pipes viewed as from the remote side in Figure 1, showing the manner of directing the spray or blast.

Figure 4 is a similar view showing a different distribution of the blast.

Figure 5 is a fragmentary view of two distributing pipes broken away for purposes of illustration, the same being adjacent pipes.

from which co-operating nozzles of the same groups are fed.

Figure 6 is a view taken at right angles to the plane of Figure 5 looking from the right 5 of the apparatus as shown in Figure 5.

Figure 7 is a figure corresponding to Figures 3 and 4 showing the distributing pipes with the nozzles grouped in threes.

Figure 8 is a plan view of Figure 7.

10 Figure 9 is an elevation of the water jacketed unit looking from the rear, i. e., the bridge wall end of the furnace toward the front.

15 Figure 10 is an end elevation of the same looking from the left in Figure 9.

20 Referring to the drawing by numerals, the installation shown in Figure 1 includes a drum 1, headers 2 and 3 connected to opposite ends of the drum, the header 3 being lowest, and a nest of tubes 4 having the usual incline leading from the lower header 3 to the upper header 2. These tubes may have the usual or any suitable arrangement. They are located in a furnace 5 having a 25 bridge wall 6 beyond which is a flue 7.

25 Crossing the group or nest of tubes 4 at right angles, preferably above and below the tubes and suitably spaced so that the steam can reach all of the surfaces which it is desired to clean, as hereinafter to be described, I have shown pairs 10 of distributing tubes 30 11, 12. These are preferably clamped together in close parallel arrangement, as shown in Figures 5 and 6, the clamps being indicated by reference character 13. Steam or other suitable fluid under pressure is supplied to these pairs of distributor tubes 10 from any available source. In the present instance I have shown a pipe connection 15 40 from a steam header 16 to a main 17 which runs along the base of the furnace. This header 17 is connected to each distributor 11, 12 of each pair of parallel distributors 10 by suitable risers 19, 20 preferably arranged in 45 pairs or otherwise for the purpose of permitting or providing for an independent variation of the relative pressure in the distributors of each pair. The risers 19, 20 are each connected to the respective corresponding 50 distributors 11, 12 by means of elbows 21, 22 which, as shown, are tapered to offer as little impediment as possible to the velocity of the steam flowing to the distributors, and the respective risers are controlled by a 55 valve in each riser, see valve 23 in each riser 19 and valve 24 in each riser 20.

55 The pairs 10 of distributors 11, 12 carry the pairs 25 of corresponding converging nozzles 27, 28. These nozzles as shown, see 60 Figures 3 and 4, are arranged at 90°, but the angle is merely a matter of distribution of the blast and determination of the surface to be swept by the particular pair of nozzles affected and determination of the angle to 65 which the direction of the blast may be va-

ried. The pairs of nozzles 25, see Figure 2, are spaced in accordance with the spacing of the tubes so as to reach and sweep the desired surfaces, the important point being that each tube of each pair of tubes 10 supports one nozzle of each pair of nozzles 25 that the supply of fluid to each nozzle is separately controlled, so that by changing this pressure the angle of the resultant blast or spray may be swung through an angle 75 equal to or substantially equal to the angle at which the nozzles converge, the term converge being used in the sense that the center lines of the streams from the perspective nozzles intersect or substantially intersect. 80

The lower and forward group of distributor tubes, see Figure 1, indicated by reference character 42, is, as will be noted, so located that it is subject to almost the maximum heat of the furnace. Wherefore it is 85 found necessary to jacket this group of tubes in order to protect and preserve it from burning. This jacket is indicated in a general way by reference character 43. Water is supplied to the jacket from the mud drum 90 44 by way of a pipe connection 45 and led back to the boiler from the jacket by a pipe connection 46. This jacketed unit or group is illustrated in detail in Figures 9 and 10. The same consists of two pipes 47 of almost 95 twice the diameter of the distributor pipes 11, 12. These are connected at their remote ends by a suitable fitting 48 having plugs 49 which may be utilized in the insertion or removal of the steam pipes or otherwise. At 100 the near end, as seen in Figure 1, and at the left in Figure 9, these pipes are connected by a special fitting 50 having a central partition 51 to separate the upper and lower 105 parts of the jacket to cause the water to circulate along the length of the pipes. It is also tapped at the bottom 52 for connection to the water supply pipe 45 and at the top at 53 for connection to the return pipe 46. This fitting is also shown as having openings 110 opposite the ends of the distributor pipes indicated by reference character 54, the same being closed by any suitable means 55. The steam risers 19, 20 are connected to the steam distributor pipes 11, 12 by means 115 of corresponding pipe connections 56, 57 which pass through this fitting as indicated, being suitably connected to the steam pipe by elbows 58, 59 inside the fitting 50. The openings which admit these pipes to the fitting 50 may have the necessary fit or be otherwise suitably packed as indicated at 60. The nozzles carried by these tubes have a long threaded shank 61 which co-operates 120 with threaded openings 62, 63 in the steam pipe and jacket, respectively. As will be noted the opening 64 at the mouth of each nozzle is preferably elongated at right angles to the plane in which the nozzles converge. 125 130

The group of distributor tubes, or as many of them as desired, may be provided with a pilot or indicator nozzle 65 outside the furnace in plain view of the operator, and each 5 being connected to both the corresponding elbows 21, 22 by suitable fittings as indicated, the pilot or indicator nozzle having converging nozzle openings 66, 67 at the same angle as those within the boiler carried 10 by the corresponding distributor tubes but preferably of less capacity. The object of this is to indicate to the operator the direction taken by the steam jets as they are varied in the use of the apparatus.

15 In Figure 7 I have shown a modified form of the invention in which distributors 31, 32, 33 are arranged in groups 35 of three distributor tubes in a group, and the nozzles are correspondingly arranged in groups of 20 three including a nozzle 36, 37, 38 of each group carried by each corresponding pipe 31, 32, 33 so that each group of nozzles is composed of three converging nozzles, and the direction of the blast may be thus universally controlled instead of being confined 25 in its direction to a single plane as in the instance of nozzles arranged in pairs. The nozzles shown in Figure 7 are intended to converge toward a single point indicated 30 by 40 in this figure.

As already pointed out, the distributor tubes are arranged in groups 10 and 35 of two substantially parallel tubes 11, 12 or three substantially parallel tubes 31, 32, 33, 35 or the desired number, and the nozzles carried by each such group of tubes are arranged in a series of groups or sets. Each nozzle of each set, to be most effective in accordance with the invention, should be separately fed or otherwise arranged so that the pressure of this nozzle may be controlled independently of the other nozzles of the same set. Therefore the number of distributor tubes in a group is logically made to 40 equal the number of nozzles in each group or set fed by the tubes without regard to the number of sets, the object being to provide the necessary number of groups of converging nozzles and means for supplying fluid under pressure to each nozzle, and means for controlling the pressure at some of the nozzles of each of several of the groups independently of the other nozzles of the group, or more particularly, of varying 45 the relative velocity and pressure of the jet from the respective converging nozzles composing any group. Preferably all the nozzles of the apparatus are so arranged in the desired number of groups and the nozzles in the groups are all so relatively controlled.

The operation of the device will be clearly apparent from the preamble taken with the description and the drawings. Briefly considered; any suitable fluid under pressure,

as steam, which is of course most conveniently available in boiler installations, is supplied to the main 15 from a convenient source as the steam header 16. This supply, being controlled by valves 23, 24 in the respective pairs of distributor tubes 11, 12, is so manipulated as to change the relative pressure at the nozzles composing each or any group or pair, and hence the relative velocity of the respective jets composing the 75 combined jet from each group of two or three or more converging nozzles so that the combined jet from each such group is swung through an arc or cone limited by the angle at which the nozzles converge, causing each such combined jet to sweep a corresponding area of heating surface.

I have thus described specifically and in detail an apparatus embodying my invention in order that its nature and the manner of operating it may be clearly understood; however, the specific terms herein are used in the descriptive rather than in the limiting sense, the scope of the invention being defined in the claims.

What I claim and desire to secure by Letters Patent is:

1. In a soot blowing or similar apparatus, means for directing and varying the direction of a fluid jet consisting of a plurality of converging nozzles, means for supplying fluid under pressure to each nozzle, and means for varying the relation which the pressure and velocity of the supply of fluid to one of said converging nozzles bears to the pressure and velocity of the supply to another of said nozzles.

2. In a soot blowing or similar apparatus, means for directing and controlling the direction of a fluid jet consisting of a plurality of converging nozzles, the jets from which meet and unite to form a single jet, and means for varying the relative pressure and velocity of the supply to the respective nozzles.

3. In a soot blowing apparatus, a plurality of sets of converging nozzles directed at the heating surface of a boiler, means for supplying fluid under pressure to each of the nozzles of each set, having a single jet for each set, and means for controlling the supply of fluid to one nozzle of each set and varying the pressure and velocity of said supply relatively to the pressure and velocity of the supply to another nozzle of each set.

4. In combination with a boiler, a soot blower consisting of a plurality of sets of nozzles, the nozzles of each set converging to form a single jet directed at the heating surface, separate means for supplying fluid under pressure to each of a plurality of nozzles of each set, and means for varying the relation borne by the supply to part of the nozzles in each of the sets to the supply to

the remainder of the nozzles in said sets to vary the direction of the jets to cause them to engage different and varying areas of the heating surface.

5. A soot blower consisting of a number of units, each unit comprising a plurality of converging nozzles, means for supplying fluid under pressure to each said nozzle, and means for varying the relation borne by

the supply to part of the nozzles in each unit to the supply to the remainder of the nozzles in said units.

Signed by me at Baltimore, Maryland, this 5th day of September, 1919.

PHILIP W. DALRYMPLE.
